UNITED STATES PATENT OFFICE.

RAYMOND B. PRICE, OF NEW YORK, N. Y., AND CLIFFORD LEE, OF NAUGATUCK, CONNECTICUT, ASSIGNEES TO THE GOODYEAR'S METALLIC RUBBER SHOE COMPANY, A CORPORATION OF CONNECTICUT.

VENTILATED BOOT OR SHOE.

1,260,942.

Specification of Letters Patent. Patented Mar. 26, 1918.

Application filed December 7, 1914. Serial No. 875,796.

To all whom it may concern:

Be it known that we, RAYMOND B. PRICE and CLIFFORD LEE, both citizens of the United States, and residents of the city of 5 New York, county and State of New York, and Naugatuck, county of New Haven, State of Connecticut, respectively, have invented certain new and useful Improvements in Ventilated Boots or Shoes, of which the following is a full, clear, and exact disclosure.

This invention relates to ventilated boots, shoes, etc., and has for an object to provide a self-contained, positively acting device operative by movement of the wearer's foot for 15 removing air from contact with the foot and preventing its coming again into contact therewith undiluted.

Exudations come from the foot in the form of vapor and this vapor is often condensed and accumulates as moisture upon the 20 inside of the article of footwear with attendant discomfort to the wearer. Excess humidity within the article of footwear is another cause of discomfort. The capacity of 25 footwear for permitting transpiration, determines to a great extent the amount of moisture accumulation upon the sock or humidity within the article of footwear.

In footwear formed of leather, rubber, or 30 other well known materials, whose transpiration-permitting qualities are limited, attempts have been made to obviate excess humidity and moisture accumulation by introducing air into or withdrawing air from the 35 article of footwear, but at best these attempts have produced wholly or in part a churning of air around the foot, and this is inadequate for attaining the results sought.

The solution of this problem lies in producing a positive withdrawal of exudations 40 from around the foot and expulsion of the same into the exterior atmosphere as fast as given off by the foot. To attain this end, I provide a compact self-contained bellows 45 concealed in the bottom of the boot or shoe and operated by the pressure of the foot at each step to cause a positive current of air to flow from around the foot to the exterior atmosphere. Experiment has proved that 50 a large volume of air should be withdrawn, not less than 5 c. c., under average conditions, at a step to prevent moisture accumulation and insure comfort. To accomplish this, I provide in connection with the bel-

lows, novel air ducts through which the bellows can readily exhaust the necessary volume of air, suitable check valves being provided to prevent reverse movement of the air.

The invention can readily be understood 60 from the following description, reference being made to the accompanying drawings, in which—

Figure 1 is a plan view of an insole embodying my invention;

Fig. 2 is a longitudinal sectional view on the line 2—2 Fig. 1;

Fig. 3 is a cross-sectional view on the line 3—3, Fig. 1;

Fig. 4 is a plan view of the parts shown 70 in Fig. 1 with parts removed and parts in section.

I may incorporate the invention in the outsole, insole, outheel, inheel, or any attachment of these parts, or even in the arch of 75 the boot or shoe, regardless of whether said parts are integral or separate from the boot or shoe, and for the purposes of illustration, I will illustrate the invention in connection with an insole which I construct of a top 80 layer 10, preferably of rubber skim coated fabric, and a bottom layer 11, preferably of sheet rubber, the bottom layer having formed integral therewith, elastic pegs 12. Both layers are separated at the edges by a 85 gasket 13 preferably of rubber, cemented or otherwise secured airtight to both layers. The gasket has formed integral therewith at the instep or shank of the insole a cross piece which constitutes a valve chest 14, the same 90 dividing the space within the inclosure of the gasket into two airtight chambers, one at the toe and the other at the heel of the insole.

Supported by the pegs 12 of the toe and 95 heel chambers respectively, are stiff plates 15 and 16 of wood fiber, metal or other suitable material, these plates being smaller in size than their respective chambers and being forced down with the top layer to simultaneously compress the elastic pegs beneath them when subjected to pressure by the foot in walking and being raised by the return of the pegs to normal condition upon the pressure being released, whereby two bellows 100 chambers 17 and 18 are formed, one at the toe and the other at the heel of the insole.

Secured to the bottom face of the top layer

10 is a narrow strip 19, preferably of rubber, upon which longitudinal threads 20 of rubber, fabric or other suitable material are molded, cemented, or otherwise secured to 5 form air ducts 20', which extend longitudinally of the top layer, the marginal edges of the strip being cemented or otherwise secured air-tight to the top layer, to seal these ducts from both bellows. Communication 10 between the air ducts and the sole of the foot is established by means of staggered perforations 21, formed along the medial longitudinal diameter of the top layer, and communication between these ducts and the 15 valve chest is established through an opening 22 in the strip 19.

The valve chest 14 is formed with an inlet passage 23 which communicates with the air ducts through the opening 22 and which 20 communicates with the toe and heel bellows through respective ports which are controlled by check valves 24 and 25 that open 25 toward the bellows and prevent backward movement of the air therefrom into the valve chest. The valve chest is also provided with an exhaust passage 26 which communicates with the toe and heel bellows through respective ports which are controlled by check valves 27 and 28 that open 30 toward the exhaust passage and prevent backward movement of the air therefrom into the bellows. An outlet pipe 29 is connected with the exhaust passage and may be conducted through the upper of the boot or 35 shoe, equipped with the insole to establish communication between the exhaust passage and atmosphere.

In operation when the wearer plants the 40 foot upon the ground, the pressure of the foot compresses the bellows with a resultant forcing of their contained air through the check valves 27 and 28 into the exhaust passage 26 and from thence through the tube 29 to the atmosphere. Upon the foot being 45 lifted, the pressure upon the bellows is released, whereupon the same expand to normal position with a resultant creation of a partial vacuum which causes a suction of air downward in the article of footwear and 50 across the sole of the foot through the perforations 21, air ducts 20', opening 22, inlet passage 23 and check valves 24 and 25, to satisfy the partial vacuum in the bellows, this air being expelled to the exterior atmosphere upon the foot again being planted 55 upon the ground, as above described.

While I have shown and described a structure for practising my invention, I do not limit myself to the particular structure 60 shown and described, since it is simply essential to the practice of my invention that a bottom portion of a boot or shoe be con-

structed to provide a self-contained bellows in connection with air channels and suitable check valves to make the action of the air 65 positive.

What I claim and desire to protect by Letters Patent is:

1. In a boot or shoe, air ducts, bellows sealed airtight from the air ducts, a valve 70 chest communicating with the bellows and with the air ducts, and inlet and exhaust valves in the valve chest permitting the passage of air through the chest in a continuous direction. 75

2. In a boot or shoe, air ducts having inlet openings arranged to communicate with the sole of the wearer's foot, bellows sealed airtight from the air ducts, a valve chest 80 communicating with the bellows and with the air ducts, and inlet and exhaust valves in the valve chest for permitting the passage of air therethrough in a continuous direction.

3. In a boot or shoe, air ducts, bellows sealed airtight from the air ducts, a valve chest having an inlet passage communicating with the air ducts and having an outlet passage, check valves in the valve chest preventing retrograde movement of air from 90 the bellows to the air ducts, and check valves in the valve chest preventing retrograde movement of air from the outlet passage to the bellows.

4. In a boot or shoe, a toe bellows, a heel bellows, air ducts communicating with the interior of the boot or shoe, a valve chest communicating with the bellows and with the air ducts, check valves permitting the passage of air from the valve chest into the 100 bellows, and check valves permitting the passage of air from the bellows to the atmosphere.

5. In a boot or shoe, air ducts communicating with the interior of the boot or shoe, 105 a valve chest, bellows having communication with the air ducts and with the atmosphere through the valve chest, and check valves in the valve chest permitting the bellows only to alternately suck air through the 110 ducts and exhaust it into the atmosphere.

Signed as New York, N. Y., Nov. 30th, 1914.
